ABSTRACT

A mounting system for an industrial compression system including a first component close-coupled to a second component includes a first support for the first component. The first support is configured to resist movement of the first component in a first direction substantially horizontal relative to the first component, a second direction substantially vertical relative to the first component, and an axial direction relative to the first component. The mounting system also includes a second support for the second component. The second support is configured to resist movement of the second component in a first direction substantially horizontal relative to the second component and a second direction substantially vertical relative to the second component, wherein the second support permits movement of the second component in an axial direction relative to the second component.

1
COMPRESSOR MOUNTING SYSTEM

CROSS REFERENCE

This application is a United States national phase application of co-pending international patent application number PCT/US2007/079350, filed Sep. 25, 2007, which claims priority to U.S. Provisional Patent Application No. 60/826,876, filed Sep. 25, 2006, the disclosures of which are incorporated herein by reference.

BACKGROUND

The present invention relates to compressor mounting systems and, more particularly, to a pedestal based mounting system for a close-coupled industrial compression system including heat exchangers and gas break vessels.

As compression system technology has advanced, compression systems have become increasingly sophisticated and energy efficient. For example, heat exchangers and gas break vessels have been incorporated into compression systems as separate components integrated with the compressor and motor driver to improve system performance and efficiency. As a result of incorporating additional features such as heat exchangers, industrial compression systems have become larger and are commonly mounted with components connected end-to-end in a compression system train. While performance and efficiency has improved in these types of systems, the size and weight of such systems has grown.

To incorporate performance and efficiency advantages of components, such as heat exchangers, while maintaining a smaller package, a type of compression system is provided with a compressor close-coupled to an electric motor driver. This arrangement allows for a compact design with benefits over traditional base-plate mounted compressor trains. A further extension of this concept is to incorporate process heat exchangers into a compact interconnected package. Currently, process heat exchangers are mounted remotely from the compressor with long, voluminous extensions of interconnected process piping.

SUMMARY

In one embodiment, the invention provides a mounting system for an industrial compression system including a first component close-coupled to a second component. The mounting system includes a first support for the first component, the first support configured to resist movement of the first component in a first direction substantially horizontal relative to the first component, a second direction substantially vertical relative to the first component, and an axial direction relative to the first component. The mounting system also includes a second support for the second component, the second support configured to resist movement of the second component in a first direction substantially horizontal relative to the second component and a second direction substantially vertical relative to the second component, wherein the second support permits movement of the second component in an axial direction relative to the second component.

In another embodiment, the invention provides a mounting system for a compression system having a motor dual-ended to a first compressor and a second compressor. The mounting system includes a first support for the first compressor, the first support configured to resist movement of the first compressor in a first direction substantially horizontal relative to the first compressor, a second direction substantially vertical relative to the first compressor, and an axial direction. The

mounting system also includes a second support for the second compressor, the second support configured to resist movement of the second compressor in a first direction substantially horizontal relative to the first compressor, a second direction substantially vertical relative to the second compressor, and an axial direction. A beam extends between the first and second supports, wherein the beam supports the motor, and further wherein movement of the motor is permitted in an axial direction.

10 Other aspects of the invention will become apparent by consideration of the detailed description and accompanying drawings.

BRIEF DESCRIPTION OF THE DRAWINGS

15 FIG. 1 is a perspective view of a close-coupled industrial compression system including a compressor mounting system according to one embodiment of the invention.

20 FIG. 2 is a front perspective view of the compressor mounting system shown in FIG. 1.

25 FIG. 3 is a rear perspective view of the compression system shown in FIG. 1, and illustrates lifting and transporting features of the compressor mounting system.

30 FIG. 4 is a bottom perspective view of the compressor mounting system shown in FIG. 1.

35 FIG. 5 is a perspective view of a compressor mounting system according to another embodiment of the invention, and configured for use with a close-coupled, single drive, dual-compressor system.

40 FIG. 6 is a bottom perspective view of the compressor mounting system shown in FIG. 5.

45 Before any embodiments of the invention are explained in detail, it is to be understood that the invention is not limited in its application to the details of construction and the arrangement of components set forth in the following description or illustrated in the following drawings. The invention is capable of other embodiments and of being practiced or of being carried out in various ways. Also, it is to be understood that the phraseology and terminology used herein is for the purpose of description and should not be regarded as limiting.

50 For example, terms like "central", "upper", "lower", "front", "rear", and the like are only used to simplify description of the present invention, and do not alone indicate or imply that the device or element referred to must have a particular orientation. The elements of the industrial compressor mounting system referred to in the present invention can be installed and operated in any workable orientation desired. In addition, terms such as "first", "second", and "third", are used herein for purposes of description and are not intended to indicate or imply relative importance or significance.

DETAILED DESCRIPTION

55 FIG. 1 illustrates a close-coupled industrial compression system 10 utilizing a compressor mounting system 14 according to one embodiment of the invention. A compressor 18 is connected to, and close-coupled with, a motor driver 22. Heat exchangers 26 are mounted vertically below and horizontally outward from the close-coupled system 10, and a gas break vessel 30 is mounted vertically below the compressor 18 and the motor 22. All of these components are supported and positioned by the mounting system 14. In order to place the compressor 18, the motor 22, and the heat exchangers 26 in a

60 compact package, the components are vertically and horizontally in close proximity in an interconnected relationship. The mounting system 14 may accommodate long and short time

scale positional variations between the components in order to avoid machinery misalignment and transfer of large forces between the components. Additionally, the mounting system 14 supports the weight of each of the components.

The compressor mounting system 14 includes a rigid pedestal 34, and a partially-flexible pedestal 38. The pedestals 34, 38 provide a combination of rigid and flexible support that enables close-coupled, interconnection and support of the components of the industrial compression system 10. The mounting system 14 provides rigid support to the components that require rigid support (e.g., the compressor 18) and simultaneously provides flexible support of certain components (e.g., the motor 22) to permit relative movement in directions that are beneficial to operation and performance of the system 10. The mounting system 14 positions components vertically and horizontally with respect to each other in close proximity while permitting appropriate relative movement between the components.

Referring to FIGS. 1 and 2, the pedestal 34 includes a generally rectangular pedestal plate 42 positioned approximately vertically under a center of mass CM-C of the compressor 18. The pedestal plate 42 includes openings 46 to position and support the heat exchangers 26 of the industrial compression system 10, whereby vessel supports 50 are positioned between the heat exchangers 26 and the plate 42. An opening 54 is also provided in the plate 42 for supporting the gas break vessel 30. An upper portion 42A of the plate 42 includes a flange plate 58 combined with a casing mount 62 for supporting the compressor 18 on the pedestal 34. In the illustrated embodiment, the rigid pedestal 34 is formed from a single plate; however, it should be readily apparent to those of skill in the art that in further embodiments any number of pedestal plates may be used (e.g., two plates axially coupled together). In still another embodiment, the plate may be fabricated from bolted sections split at the heat exchanger interface to allow easier assembly of the heat exchangers into the system 10.

The pedestal 34 supports the compressor 18, and is rigid, or stiff, in a vertical direction (generally along the Y-axis) and a horizontal direction (generally along the X-axis) relative to a supporting surface 66, as well as in an axial direction (generally along the Z-axis) of the compressor 18. It is generally desirable to support the compressor 18 in a fixed position. Rigidity is given to the pedestal 34 through a selection of material thickness of the plate 42 and appropriate structural re-enforcement.

The partially-flexible pedestal 38, is positioned approximately vertically under a center of mass CM-M of the motor 22, axially spaced from the pedestal 34. The pedestal 38 is rigid in a vertical direction (generally along the Y-axis) and a horizontal direction (generally along the X-axis) relative to the supporting surface 66, but is flexible, soft or compliant in an axial direction (generally along the Z-axis) relative to the motor 22. The pedestal 38 includes three flex plates 70, which support the motor 22 and provide axial compliance. The pedestal plates 70 include openings 74 to position and support the heat exchangers 26 of the industrial compression system 10, whereby vessel supports 78 are positioned between the heat exchangers 26 and the plates 70. Openings 82 are also provided in the plates 70 for supporting the gas break vessel 30. The plates permit relative axial movement of the heat exchangers 26 and the gas break vessel 30. An upper portion 70A of the flex plates 70 includes a casing mount 90 for supporting the motor 22 and permitting axial movement of the motor 22.

The pedestal 38 is rigid in some directions but flexible in others to permit movement in a manner that is non-detrimental to intercomponent positioning and operation. Flexible mounting is accomplished through flexible pedestals, isolation pads or bands, flex plates and flange plates. In a further embodiment, similar axial movement flexibility is obtained

5 with a completely rigid pedestal (similar to compressor pedestal 34) including a system of axial keyways and sliding or rolling surfaces to allow the motor 22 and the heat exchangers 26 to freely move in an axial direction (generally along the Z-axis) without relatively shifting position in a vertical direction 10 (generally along the Y-axis) or a horizontal direction (generally along the X-axis).

Isolation pads 94 are positioned in multiple locations 15 within the mounting system 14 to permit relative axial movement between a structural support piece and the supported component. Referring to FIG. 2, isolation pads 94 are located at each connection between the pedestals 34, 38 and the heat exchangers 26 and the gas break vessel 30. The isolation pads 94 permit the heat exchangers 26 to move axially (and to a smaller extent, horizontally) with piping, or temperature 20 induced loads without affecting alignment of the compressor 18, the motor 22 and the interconnecting piping. The isolation pads 94 also minimize transmission of flow induced vibrations from the heat exchanger 26 to the close-coupled compressor and motor unit. In the illustrated embodiment, the 25 isolation pads 94 are formed by an elastomer band. In further embodiments, flexible support may be provided by other means, such as elastomer-mounted rollers, low friction pads, anti-friction bearings, or the like, to allow a larger degree of relative axial movement.

30 FIG. 3 illustrates a lifting system 98 that permits the industrial compression system 10 to be lifted and transported as a complete unit. The lifting system 98 includes lifting lugs 102 positioned at appropriate and strategic locations on the pedestals 34, 38. The lifting lugs 102 are connected with cables 35 106, or similar structures, such as rods, to a single point lift 110. The compression system 10 is lifted and transported through the single point lift 110.

As shown in FIG. 4, the industrial compression system 10, 40 along with the pedestals 34, 38, is supported by a three point mounting base system. The mounting base system includes two pedestal base supports 114 positioned on a lower face, and at each end, of the plates 42 of the pedestal 34. A third base support 118 is centrally located at a lower face of the plates 70 of the pedestal 30. The three base supports provide structural de-coupling between sub-base structures carrying the compression system 10 (such as an off-shore oil platform) and the compression system 10 itself. In a further embodiment, other base systems may be used.

It should be readily appreciated that the mounting system 50 14, as shown in FIGS. 1-4, supports the compressor 18, the motor 22, heat exchangers 26 and the gas break vessel 30 in a single package forming a relatively compact group of components. Thereby, interconnecting piping between components are shorter and comprised of smaller diameter piping 55 than is typical in a widely-separated train-type configuration. Interconnecting mechanical structures, such as drive components between the motor driver 22 and the compressor 18 are also made shorter and more compact.

60 A combination of support structures form the mounting system 14, some of which are rigid in all three primary directions (generally along the X, Y, and Z axes illustrated in FIG. 1) and at least one of which is flexible in, at least, an axial direction (generally along the Z-axis illustrated in FIG. 1), and are combined to permit relative movement of close-coupled components in a manner that is beneficial to operation 65 or performance of the compression system. While reference is made herein to the compressor mounting system 14

utilizing a single, rigid pedestal 34 and a single, combination rigid and flexible pedestal 38, it is contemplated that other embodiments of the invention may utilize any number of each of the rigid pedestal and the combination rigid and flexible pedestal. It should be readily apparent to those of skill in the art that in a further embodiment, the pedestals 34, 38 may be reversed such that the rigid pedestal 34 supports the motor 22 and the partially-flexible pedestal 38 supports the compressor 18.

FIGS. 5 and 6 illustrate a compressor mounting system 200 according to another embodiment of the invention. An industrial compression system 214 is a double compressor drive arrangement including a single electrical drive 226 dual-ended to power two compressors 222. Similar to the compression system 10 shown in FIGS. 1-4, heat exchangers 26 are mounted vertically below and horizontally outward from the close-coupled system 214, and gas break vessel 30 is mounted vertically below the compressors 222. All of these components are supported and positioned by the mounting system 200. In order to place the compressors 222, the motor 226 and the heat exchangers 26 in a compact package, the components are vertically and horizontally in close proximity and in an interconnected relationship.

The mounting system 200 employs isolation pads, flange plates and flex plates to permit positional variation of the components in specific locations and directions that are beneficial to system operation and performance. The mounting system 200 includes two rigid pedestals 230, 234, each of which supports a compressor 222 at a position close to the compressor's center of mass. The pedestals 230, 234 are connected together by a structural beam 238 extending between the pedestals 230, 234. Inter-casing flanges 242 are supported by the structural beam 238 to provide a connection that supports the compressors 222 and the motor 226. The structural beam 238 is structurally sufficient to hold the weight of the dual-ended electrical drive 226 when one or both of the compressors 222 are removed for service. The pedestals 230, 234 are also provided with openings for the heat exchangers 26 and the gas break vessels 30 which are mounted with a structure similar to the mounting utilized in FIGS. 1-4 to permit relative axial movement (generally along the Z-axis) between the pedestals 230, 234 and the heat exchangers 26 and the gas break vessels 30.

Each pedestal 230, 234 includes a plate 246 positioned under a center of mass CM-C for the respective compressor 222. Each plate 246 includes openings 250 to position and support the heat exchangers 26 of the industrial compression system 214, whereby vessel supports 254 are positioned between the heat exchangers 26 and the plates 246. A pedestal base 258 is coupled to each plate 246. Each base 258 includes openings 262 for supporting the gas break vessels 30. Each base 258 has a generally pyramidal shape for distributing weight of the compression system 10.

Referring to FIGS. 5 and 6, in the illustrated embodiment, a three point mounting base system supports the pedestals 230, 234. The first pedestal 230 includes a base mount 266 centered on a lower face of the associated pedestal base 258, and the second pedestal 234 includes a pair of base mounts 270 coupled to the lower face of the associated pedestal base 258. As discussed above, isolation pads 274 are positioned between the pedestals 230, 234 and the heat exchangers 26 and the gas break vessels 30 to permit axial movement (generally along the Z-axis) of the components without affecting alignment thereof.

The embodiments described above and illustrated in the figures are presented by way of example only and are not intended as a limitation upon the concepts and principles of

the present invention. As such, it will be appreciated by one having ordinary skill in the art that various changes in the elements and their configuration and arrangement are possible without departing from the spirit and scope of the present invention.

Since other modifications, changes and substitutions are intended in the foregoing disclosure, it is appropriate that the appended claims be construed broadly and in a manner consistent with the scope of the invention.

What is claimed is:

1. A mounting system for compression system, comprising:

a first support for a first component of the compression system, the first support comprising a pedestal plate positioned under a center of mass of the first component and configured to resist movement of the first component in a first direction substantially horizontal relative to the first component, a second direction substantially vertical relative to the first component, and an axial direction relative to the first component; and

a second support for a second component of the compression system, the second support configured to resist movement of the second component in a first direction substantially horizontal relative to the second component and a second direction substantially vertical relative to the second component, wherein the second support permits movement of the second component in an axial direction relative to the second component.

2. The mounting system of claim 1, wherein the pedestal plate is rigid in the first direction substantially horizontal relative to the first component, the second direction substantially vertical relative to the first component, and the axial direction relative to the first component.

3. The mounting system of claim 1, wherein the first support further includes a flange plate and a first casing mount for supporting the first component.

4. The mounting system of claim 1, wherein the second support comprises a plurality of flexible plates positioned under the second component, and wherein each flexible plate of the plurality of flexible plates is rigid in the first direction substantially horizontal relative to the second component and the second direction substantially vertical relative to the second component, and flexible in the axial direction relative to the second component.

5. The mounting system of claim 1, wherein the second support includes a second casing mount for supporting the second component.

6. The mounting system of claim 1, further comprising a lifting system coupled to the first and second supports for facilitating lifting of the compression system, the lifting system comprising at least one lifting lug coupled to the first support, at least one lifting lug coupled to the second support, a point lift, and cables extending between the lifting lugs and the point lift.

7. The mounting system of claim 1, wherein the compression system further comprises a plurality of components positioned below the first and second components, wherein the first and second supports further support the plurality of components.

8. The mounting system of claim 7, further comprising at least one isolation pad positioned between the first support and at least one of the plurality of components.

9. The mounting system of claim 7, further comprising at least one isolation pad positioned between the second support and at least one of the plurality of components.

10. The mounting system of claim **1**, wherein movement of the second component in the axial direction permitted by the second support is relative the first component.

11. A mounting system for a compression system, comprising:

- a first support for a first compressor of the compression system, the first support configured to resist movement of the first compressor in a first direction substantially horizontal relative to the first compressor, a second direction substantially vertical relative to the first compressor, and an axial direction;
- a second support for a second compressor of the compression system, the second support configured to resist movement of the second compressor in a first direction substantially horizontal relative to the second compressor, a second direction substantially vertical relative to the second compressor, and an axial direction, wherein the first and second compressors are coupled to the ends of a dual-ended motor; and
- a beam extending between the first and second supports, wherein the beam supports the motor, and movement of the motor is permitted in an axial direction.

12. The mounting system of claim **11**, wherein the first support comprises a plate positioned under a center of mass of

the first compressor, a base coupled to the plate, and a base mount coupled to the base and the plate for supporting the first support on a supporting surface.

13. The mounting system of claim **11**, wherein the second support comprises a plate positioned under a center of mass of the second compressor, a base coupled to the plate, and at least one base mount coupled to the base and the plate for supporting the second support on a supporting surface.

14. The mounting system of claim **11**, wherein the compression system further comprises a pair of heat exchangers positioned below the first and second compressors, wherein the first and second supports support the heat exchangers.

15. The mounting system of claim **14**, further comprising at least one isolation pad positioned between the first support and each heat exchanger.

16. The mounting system of claim **14**, further comprising at least one isolation pad positioned between the second support and each heat exchanger.

17. The mounting system of claim **11**, wherein movement of the motor in the axial direction is relative the first compressor, the second compressor, or both.
